PLUG AND JACK CONSTRUCTION

Theodore J. Obszarny, Chicago, Ill., assignor to
 Guardian Electric Mfg. Co., Chicago, Ill., a
 corporation of Illinois

Application June 21, 1937, Serial No. 149,380

6 Claims. (Cl. 173—332)

This invention relates to detachably connectable devices for completing portions of electrical circuits, and more particularly to plug and jack constructions.

5 Plug and jack constructions of the type embodying the present invention are particularly adapted for use in multiple units, including banks or groups, for simultaneously completing or breaking portions of a plurality of different 10 electrical circuits, for controlling a wide variety of electrical devices. Devices of this type, as heretofore constructed, possess several defects 15 and disadvantages which render them unsatisfactory for use in many instances, particularly where it is necessary to frequently connect and disconnect the plugs and jacks. In some constructions the jacks are formed so that they do not readily lend themselves for use in group assemblies, as they do not readily accommodate slight misalignment or variations of the co- 20 operating plugs, resulting in undue friction, and rendering it difficult to connect and disconnect the plugs and jacks. Further, the forms of jacks as heretofore constructed and used in group 25 assemblies, do not insure positive electrical contact between the plug and jack, due to slight misalignment or location of either the plugs or jacks.

One object of the present invention is to provide a novel and improved jack construction, 30 especially adapted for use in group or bank assemblies, and which permits quick and easy connection or disconnection with the cooperating plugs.

35 Another object is to provide an improved jack of the character indicated, which is self-aligning with respect to a cooperating plug to insure positive electrical contact for completing a portion of an electrical circuit.

40 A further object resides in the provision of an improved jack of the character indicated, which is constructed to cause cleansing of the surface of the plug when inserted therein and withdrawn therefrom.

45 And a further object is to provide an improved plug and jack construction which lend themselves readily for embodiment in group assemblies, and which may be economically produced.

50 Other objects and advantages will appear 55 from the following description, taken in connection with the accompanying drawing, in which:

Figure 1 is a side elevation of group plug and jack assembly, embodying the present invention,

with the plugs shown only partially entered into their cooperating jacks.

Figure 2 is an end elevation of the assembly seen in Figure 1.

Figure 3 is a perspective view of the device, 5 with the unit of plugs shown out of engagement with the jacks.

Figure 4 is a transverse section through the plug and jack assembly, taken as indicated at line 4—4 on Figure 1, showing the plugs re- 10 moved from the jacks.

Figure 5 is an enlarged perspective view of my novel and improved jack.

For the purpose of illustration I have shown in the drawing a unit including eight sets of 15 plugs and jacks, arranged in two banks of four each. It is to be understood, however, that devices of this type may be made up of various numbers of plugs and jacks in a bank or group, as desired. The device is composed of two de- 20 tachably connectible units, one carrying the plugs and the other the jacks. The unit carrying the plugs includes a panel, 10, of insulating material from which project at right angles, as seen in the drawing, a plurality of elongated 25 plugs, 11. These plugs desirably are of cylindrical, tubular form, each having a shoulder, 12, adjacent one end, seated against the surface of the panel, and the portion beyond the shoulder projects through an aperture in the panel and is 30 riveted over against the opposite side, as indicated at 14. The lower end of the plugs is rounded to facilitate their entrance into the cooperating jacks. For economy in manufacture, the plugs are spaced uniform distances apart and 35 from the marginal edge of the panel. A highly desired arrangement, as shown, is to provide a panel of proper width and mount thereon two aligned series of plugs, and, in manufacture, the panel may be in the form of a strip of sub- 40 stantial length to permit severing into lengths containing a desired number of plugs.

45 Mounted on each plug and anchored between the shoulder, 12, and the panel, is a terminal clip, 15, which extends laterally beyond the ad- 45 jacent marginal edge of the panel, 10, and having its end portion bent upwardly and formed with an aperture, 16, to provide a connection for an electrical conductor.

The unit carrying the jacks includes two 50 spaced-apart, substantially parallel co-extensive panels, 18, of insulating material supported at their opposite ends on metal supports including legs, 19, each having a foot, 21, adapted to be secured to a suitable mounting as by screws, 22. 55

The panels, 18, and supports are secured together to form a unitary assembly, and each leg has a tine, 23, struck outwardly therefrom and crimped around the lower edge of the corresponding panel, and these legs and panels are rigidly connected together by rivets, 24, with a panel, 25, of insulating material interposed between the respective pairs of legs, 19, and substantially co-extensive with the panels, 18.

10 Mounted on the outer face of each panel, 18, are a plurality of jacks, 27, spaced apart a distance corresponding substantially to the spacing of the plugs, 11, with the jacks on the opposite panels aligned in pairs. The jacks are 15 formed as metallic stampings and each includes an elongated body, 28, adapted to seat against the outer surface of the panel, and a pair of spaced-apart yieldable fingers, 30, extending outwardly at right angles to the body, and each connected 20 adjacent one end to said body. The free ends of the fingers are formed to provide a pair of cooperating, oppositely facing, convexly curved surfaces, 31, adapted to be yieldingly spread apart to accommodate a plug, 11, therebetween. The 25 curved surface portion of each finger is formed with an elongated aperture, 32, extending in the direction of the length of the fingers. These apertures are of such size and location as to serve as saddles for receiving and guiding the plugs 30 in their movement into and out of engagement with the fingers. These apertures thus tend to position the fingers relatively to the plugs and provide a contact with the plug at the edge of the slot to insure positive electrical contact between the plug and jack. Moreover, the edges of the metal around the apertures, serve as 35 scrapers for cleansing the surface of the plugs when inserted in or removed from between the yieldable fingers.

40 To anchor the jacks on the panels, 18, the upper end of the body of each jack is formed with a lug, 34, adapted to be extended through an aperture, 35, in the panel, 18, and crimped around the edge of the aperture, and the lower end of the body is formed with a lug, 36, from which a tine, 37, is struck and crimped around the lower edge of the panel, 18, as seen in Figure 4. The opening in the lug, 36, formed by the removal of the tine, serves to provide a terminal for connection of an electrical conductor. 45 The intermediate panel, 25, of insulating material, thus insures against any possible shorting of electrical circuits between the lugs of aligned pairs of jacks.

50 As may be seen in the drawing, one end of the panel, 18, extends a distance from the pair of adjacent plugs, 11, greater than at the other end, and the leg, 19, of one of the supporting brackets, projects upwardly a substantial distance above panels, 18, as indicated at 19^a, so that the upper unit carrying the plugs, 11, may only be aligned in one position for insuring engagement of the plugs, 11, with their proper corresponding jacks, 27.

55 A unit comprising an assembly or group of jacks, as herein disclosed, thus readily accommodates the plugs of the cooperating unit, so that said unit carrying the plugs may be quickly and easily attached to, or detached from, the 60 unit carrying the jacks, and insures positive electrical contact between each set of plugs and jacks when connected.

Although I herein show a preferred embodiment of my invention, manifestly, it is capable of modification and rearrangement without

departing from the spirit and scope thereof. I do not, therefore, wish to be understood as limiting the invention to the precise form herein disclosed, except as it may be so limited in the appended claims.

I claim:

1. In a structure of the character described, a jack unit including a panel of insulating material, and a plurality of jacks mounted in a bank on said panel with their plug openings extending in a direction substantially parallel to the panel, said jacks being adapted for cooperation with a plurality of plugs arranged in a bank to complete portions of a plurality of different electrical circuits, said jacks each being formed as stampings, including a body mounted flat against the panel, and a pair of spaced-apart, yieldable elongated fingers each being solely connected adjacent its lower end to said body, and the upper ends of said fingers being free and yieldable away from each other, the free ends of said fingers being formed to present a pair of cooperating, oppositely facing, convexly curved surfaces extending in the general direction of the length of said fingers for embracing the surface of a plug extending parallel to said panel. 10
2. In a structure of the character described, a jack unit including a panel of insulating material, and a plurality of jacks mounted in a bank on said panel with their plug openings extending in a direction substantially parallel to the panel, said jacks being adapted for cooperation with a plurality of plugs arranged in a bank to complete portions of a plurality of different electrical circuits, said jacks each being formed as stampings, including a body, and a pair of spaced-apart, yieldable, elongated fingers each being solely connected adjacent one end to the body, the opposite end of one of said fingers being free and yieldable away from the other, the opposite ends of said fingers being formed to present a pair of cooperating, oppositely facing, convexly curved surfaces extending in the general direction of the length of said fingers for embracing the surface of a plug extending parallel to said panel. 15
3. As an article of manufacture, a jack formed as a metallic stamping and comprising a substantially flat body, and a pair of spaced-apart, yieldable fingers, formed at right angles to and extending in the general direction of the body and each of said fingers being solely connected adjacent its lower end to said body and the upper ends of said fingers being free and yieldable away from each other, the free ends of the fingers being formed to provide a pair of cooperating, oppositely facing, convexly curved surfaces, extending in the general direction of the length of said fingers. 20
4. As an article of manufacture, a jack formed as a metallic stamping and comprising a substantially flat body, and a pair of spaced-apart, yieldable fingers, formed at right angles to and extending in the general direction of the body and each being connected adjacent its lower end to 25 said body, the free ends of the fingers being formed to provide a pair of cooperating, oppositely facing, convexly curved surfaces, extending in the general direction of the length of said fingers, the body including a lug portion below 30 the connection of the fingers and having a tine struck therefrom to provide means for anchoring the body to a mounting, and the opening formed by removal of the tine serving to provide a connection for an electrical conductor. 35

5. As an article of manufacture, a jack formed
as a metallic stamping and comprising a substan-
tially flat body, and a pair of spaced-apart, yield-
able fingers, formed at right angles to and ex-
tending in the general direction of the body and
each being connected adjacent its lower end to
said body, the free upper ends of the fingers
being formed to provide a pair of co-operating,
oppositely facing, convexly curved surfaces, ex-
tending in the general direction of the length of
the fingers, the body including lugs at upper
and lower ends, the lower lug having a tine struck
therefrom which, together with the upper lug,
provides means for anchoring the body to a
mounting, the opening formed in the lower lug
by removal of the tine serving to provide a con-
nection for an electrical conductor.

6. As an article of manufacture, a jack formed
as a metallic stamping and comprising a body
including a pair of spaced-apart yieldable fin-
gers each being solely connected adjacent one
end to said body, the opposite end of one of
said fingers being free and yieldable away from
the other, said opposite ends of said fingers being
formed to provide a pair of cooperating, oppo-
sitely facing, convexly curved surfaces extend-
ing in the general direction of the length of said
fingers, the convexly curved surface of one of
said fingers being formed with an elongated opening
to serve as a guide for and to assist in main-
taining a cooperating plug in proper electrical
contact with said fingers.
